Primary Examiner — Holly H Baynam

(57) CLAIM

The ornamental design for a bag cover, as shown and described.

DESCRIPTION

FIG. 1 is an environmental front elevation view thereof with the broken lines showing a bag cover being for the purposes of environment and form no part of the claimed design;

FIG. 2 is a front view thereof;

FIG. 3 is a rear view thereof;

FIG. 4 is a side view thereof;

FIG. 5 is the opposite side view thereof;

FIG. 6 is a top view thereof;

FIG. 7 is a bottom view thereof;

FIG. 8 is a front view thereof; and,

FIG. 9 is a side view thereof.

In the drawings, the broken lines depict environmental subject matter only and form no part of the claimed design.

1 Claim, 8 Drawing Sheets
